(57) **CLAIM**

The ornamental design for a charger for EEG logger, as shown and described.

DESCRIPTION

FIG. 1 is a top view of a charger for an EEG logger according to the invention;

FIG. 2 is a front view of the charger for an EEG logger of FIG. 1;

FIG. 3 is a side view of the charger for an EEG logger of FIG. 1;

FIG. 4 is a rear view of the charger for an EEG logger of FIG. 1;

FIG. 5 is a bottom view of the charger for an EEG logger of FIG. 1;

FIG. 6 is a top perspective view of the charger for an EEG logger of FIG. 1; and,

FIG. 7 is another top perspective view of the charger for an EEG logger of FIG. 1, showing the EEG logger being charged.

The broken lines in FIGS. 1-6 depict portions of the charger for an EEG Logger that form no part of the claimed design. The additional broken lines in FIG. 7 depict environmental subject matter and form no part of the claimed design.
